HERBERT ABRAHAM, OF NEW YORK, N. Y., ASSIGNOR TO THE RUBEROID CO.,
A CORPORATION OF NEW JERSEY.

ROOFING SHINGLE.

Application filed April 8, 1924. Serial No. 704,962.

To all whom it may concern:

Be it known that I, HERBERT ABRAHAM, a citizen of the United States, residing at the city, county, and State of New York, ⁵ have invented a certain new and useful Improvement in Roofing Shingles, of which the following is a specification.

This invention relates to roofing shingles of the type embodying a flexible water-¹⁰ proofed backing and a slate sheet facing adhering to and covering the lower end portion of the backing to a depth greater than the extent of shingle surface which is to be exposed when such shingles are laid in over-¹⁵lapping courses.

In manufacturing the shingles the backing is waterproofed with suitable bituminous compositions of such consistency that the slate facing sheet will adhere firmly to the ²⁰ backing under the severest conditions of ordinary use, and of such degree of hardness that the backings will not stick together, at any usual atmospheric temperatures, when the shingles are packed for shipment ²⁵ or storage.

The shingles are intended to be laid principally upon pitched roofs, and there is a danger that in case of fire, or from some other extraordinary cause, the slate sheets ³⁰ may become loosened and drop off. To avoid this objection I provide a form of shingle that may be fastened to the roof by nails driven through the slate facing sheet near its upper edge in such position as to ³⁵ be covered by the lap of the next upper shingle.

Because of the slate facing sheet the lower end portion of the shingle is substantially rigid and, therefore, the shingle cannot be so ⁴⁰ nailed without causing the front end to tilt up to such an extent as to open an undesirable gap between it and the next lower shingle unless the facing sheet of the upper shingle is supported or properly elevated ⁴⁵ at its rear end.

It has been proposed to provide a shingled roofing in which the slates of each upper course are supported by separate filling layers inserted between said upper course ⁵⁰ and the next lower course, or by forming a filler on the shingle itself so that the fillers on the shingles of each course provide a support for the slates of the shingles of the next upper course. While such filling ⁵⁵ means have the advantage that they

support the slates against breakage throughout their entire lengths, the use of a separate filling layer increases the costs of material and labor required to lay the roof, and in the case where the filler forms a part of ⁶⁰ the shingle it entails difficulties in manufacture and increases the cost of the product.

According to my invention I provide a construction which enables laying of the shingles with an overlap but without necessity of using any filling means; by which the shingles of each course are so supported that they may be fastened to the roof by means of nails driven through the slate facings; and wherein nailing is accomplished ⁷⁰ with a minimum danger of breakage by affording a multi-ply cushion under the slate where the nails are driven therethrough.

In the accompanying drawings: Figure 1 is a top plan view of one of the ⁷⁵ shingles;

Fig. 2 is a longitudinal sectional view thereof, on an enlarged scale;

Fig. 3 is a top plan view of several of the shingles laid in overlapping courses; and ⁸⁰

Fig. 4 is a sectional view of the roof.

In the construction of the shingle a flexible backing 1 is employed preferably composed of roofing felt saturated with asphalt. The entire area of the backing is covered ⁸⁵ with a bituminous coating 2. A slate facing sheet 3, preferably consisting of slate veneer, is then applied to the backing in such position that it will register with an end and the adjacent sides of the completed shingle, as depicted in Figure 1, and it is affixed to the backing by adhesion to the coating.

According to this invention I employ a bituminous coating composition of such character that it shall melt to a liquid at ⁹⁵ temperatures considerably above the maximum atmospheric temperatures, that it shall not soften or run at the highest atmospheric temperatures, that its adhesion to the slate shall remain unaffected throughout the entire range of atmospheric temperatures, and that the unsurfaced portion of the coating shall be substantially non-adherent at ordinary atmospheric temperatures so as not to cause the shingles to stick together when ¹⁰⁰ they are bundled or packed for shipment. These characteristics may be obtained by using a bituminous coating composition having a melting point, by the ring and ball method, of from 180° F. to 260° F., and ¹⁰⁵ 110

having a penetration of not less than 10 in 60 seconds at 32° F. with a needle loaded 200 grams, a penetration of from 15 to 30 in 5 seconds at 77° F. with a needle loaded 5 with 100 grams, and a penetration of not greater than 50 in 5 seconds at 115° F. with a needle loaded with 50 grams. By the term "penetration" is meant, the distance 10 that a standard needle vertically penetrates the material under known conditions of loading, time and temperature. The ring and ball melting point test and the penetration test are two of the standard tests established by the American Society for Testing Materials for determining the melting point and hardness of bituminous compositions.

The slate facing sheet is preferably applied under slight pressure not only to effect 20 complete and uniform adherence to the backing but also to squeeze out a slight amount of coating at the marginal side and end edges between the facing and the backing, which squeezed portions, upon hardening 25 of the coating composition, effect a water and weather-proof sealed joint excluding moisture.

The length of the slate sheet 3, measured 30 longitudinally of the shingle, is somewhat greater than the extent which is to be exposed when the shingles are laid in overlapped relation with a substantially uniform lap, the excess length being such as to permit of nails be driven through the slate in 35 position to be covered by the lap of the next upper shingle. In actual practice the slate sheet 3 is rectangular in form, having a width transversely of the shingle of 9 inches, and a length longitudinally of the 40 shingle of 8 inches. Shingles having facings of these dimensions are intended to be laid with a depth, measured back from the front end, of 6 inches of the facing sheet exposed to the weather. It is to be understood, of course, that these dimensions may 45 be varied. In laying the shingle the fastening nails are driven through the cover portion of the facing. It has been found that nails can be driven easily through the shingle without breaking or cracking the slate facing sheet and without preformed nail holes, however, if desired, the sheet 50 may be provided with nail holes 4, or other indicia, to indicate the proper nailing points.

The backing 1 is of the width as the slate 55 facing sheet 3, but is of a length equal to three times the depth that the shingle is intended to be exposed when laid plus a distance substantially equal to the length of the cover portion of the slate facing sheet. With slate facing sheets of the dimensions 60 above-mentioned, the backing will be approximately 20 inches long because in that instance the shingle is intended to be exposed 6 inches to the weather with sub-

stantially 2 inches of the slate facing sheet covered by the lap of the next upper shingle. While the particular dimensions may be varied, the proportions described constitute an essential feature of the invention 70 because it is by designing a shingle of substantially these proportions that I am enabled to provide for laying the shingles with an overlap and without necessity of using any filling means.

Referring now to Figure 3, showing an indeterminate portion of a roof covering formed of shingles laid in overlapping course, it will be seen that the shingles of course A are fastened to the roof by nails 80 5 driven through the slate facing sheet in position to be covered by the lap of the ensuing course B, and that the upper ends of the backings 1 of the shingles of course A extend up under the upper edges of the slate facing sheets 3 of the shingles of the second ensuing course C. Each course is similarly laid and fastened, and it will be observed that the nails not only pass through the shingles of the course being nailed but 90 also through the backings of the shingles of the next two lower courses, thus providing a multiply cushion in nailing.

Should the shingles be of such lengths 95 that when laid the upper ends of those of any course do not extend up to the nailing points of the second ensuing course, then in nailing the shingles of the last mentioned course they will tilt on the upper edge of the slate facing sheet of the immediately underlying shingle, acting as a fulcrum, to such extent as to form an unsightly gap between the front end of the shingle being nailed and the facing of the underlying one.

By providing a construction wherein the 100 lengths of the shingles is such that when laid the rear ends of those of any course extend upwards of the nailing points of the second ensuing course, the slate sheets of the shingles of the last mentioned course will be supported, at and about the nailing points, by the combined backings of the shingles of the two underlying courses, and tipping or breakage of the slate faced ends will be prevented on driving the nails home. Also, 110 it will be noted, that this construction results in each shingle being held to the roof by six nails, assuring that the shingles will be fastened securely and flat, and without danger of any of the slate sheets dropping 115 off.

What I claim is:

1. A roofing shingle adapted with similar shingles to be laid in overlapping courses 125 having a substantially uniform lap, each comprising a flexible waterproof backing and a slate sheet facing adhering to the backing in registration with an end and the adjacent sides thereof, the slate sheet being 130 of a length, measured longitudinally of the

shingle, greater than the depth to which the shingle is intended to be exposed when laid, and the backing being of a length greater than three times said depth of exposure.

2. A roofing shingle adapted with similar shingles to be laid in overlapping courses having a substantially uniform lap, each comprising a flexible waterproof backing 10 and a slate sheet facing adhering to the backing in registration with an end and the adjacent sides thereof, the slate sheet being of a length, measured longitudinally of the shingle, greater than the depth to 15 which the shingle is intended to be exposed when laid by an amount sufficient to permit nailing through the unexposed portion of the facing, and the backing being of a length greater than three times the depth of exposure by an amount substantially equal 20 to the length of the said unexposed portion of the facing.
3. A roofing shingle adapted with similar shingles to be laid in overlapping courses 25 having a substantially uniform lap, each comprising a flexible waterproof backing,

a bituminous coating on the backing having adhesive properties when heated but being non-adhesive at atmospheric temperatures, and a slate sheet facing adhering to the 30 coating in registration with an end and the adjacent sides of the backing, the slate sheet being of a length, measured longitudinally of the shingle, greater than the depth to which the shingle is intended to be exposed 35 when laid, and the backing being of a length greater than three times said depth of exposure.

4. A roof composed of a plurality of shingles, each comprising a flexible waterproof backing and a slate sheet facing on an end portion of the backing, laid in overlapping courses having a substantially uniform lap, each course being fastened by 40 nails driven through the slate facings in 45 position to be covered by the lap of the shingles of the succeeding course, and with the rear ends of the backings of the shingles of each course extending upwards of nailing points of the shingles of the second 50 ensuing course.

HERBERT ABRAHAM.
